FUEL PUMP

Arthur Alexander Sidney, Thornton Heath, England, assignor to Bryce Limited, a company of Great Britain

Application February 16, 1933, Serial No. 657,115
In Great Britain January 21, 1932

1 Claim. (Cl. 103—41)

The invention relates to pumps for supplying fuel to internal combustion engines and more particularly to pumps of the type in which fuel is drawn or forced into a cylinder from where it is expelled by a plunger sliding therein with a constant stroke.

The object of the invention is to provide a pump of the type set forth, from which fuel is expelled only during the middle and latter portions of the plunger stroke, and in which the duration of the working portion of the stroke may be shortened or lengthened, as and when desired, the commencement of the pumping occurring always at the same point in the stroke of the plunger.

According to the invention the plunger is provided at a short distance from its working face with a diametral hole, and an axial or longitudinal hole is drilled in the working face of the plunger, which terminates at the other end in the diametral hole. The cylinder is provided with a port or with a pair of diametrically disposed ports, which are so positioned in the cylinder as always to be uncovered by the plunger during the initial portion of its working stroke, and to co-operate to a greater or lesser extent with the diametral hole in the plunger during the final portion of the working stroke of the plunger. The plunger and cylinder are arranged for axial rotation relatively to one another to bring the diametral hole in the plunger into co-operation with the ports in the cylinder to a greater or lesser extent. Preferably, the plunger is mounted for rotation relatively to the cylinder and the cylinder is conveniently constituted by a sleeve member secured within the pump body.

The edges of the by-passing port or ports which determine the termination of the initial by-passing and the commencement of the final by-passing are preferably inclined with respect to each other. Conveniently the ports are of triangular shape with their upper edges perpendicular to the axis of the cylinder. The greatest axial distance between the two working edges of the port or ports is always greater than the distance between the working face of the plunger and the nearest edge of its diametral hole.

One or more additional diametral holes may be provided in the plunger so as to communicate with the axial hole, in which case corresponding pairs of by-passing ports are provided in the cylinder.

The invention is illustrated somewhat dia-

grammatically by way of example in the accompanying drawing, in which Fig. 1 shows a part of a fuel pump for internal combustion engines, including a plunger disposed within a sleeve member and adapted for axial rotation 60 relatively thereto.

Fig. 2 is a side elevational view of the sleeve showing the by-passing ports therein and

Fig. 3 is a diagrammatic representation showing the development of one of the ports in the sleeve and illustrating the relative positions of the diametral passageway in the plunger with respect to this port for various fuel deliveries of the pump.

Referring to the drawing, the pump comprises a vertically disposed cylindrical sleeve 1 which is secured within the pump casing 2. The sleeve is provided with two diametrically disposed ports 3 and 4 whereby the interior 70 of the sleeve may be put into communication with an annular channel 5 in the pump casing, surrounding the sleeve. This channel 5 communicates with a passageway 6 connected to a supply of fuel under pressure. The upper end 75 of the sleeve 1 is provided with a seat which is closed by a steel ball valve 7 biased thereto by a coil spring 8 with a pressure somewhat in excess of the supply pressure of the fuel. This spring pressure serves to maintain the ball 7 on its seating until the pressure exerted by the fuel within the sleeve 1 increases substantially above that at which the fuel is supplied thereto. The spring 8 is housed within a union member 9, which is screwed into the upper end of the 80 pump casing 2 and serves to retain the sleeve 1 in position in the casing. A bore 10 in the union member 9 communicates with a pipe leading to the engine.

The lower end of the sleeve 1 is closed by a 85 plunger 11, which is adapted to be reciprocated in the sleeve by a cam 12 at a constant stroke. A suitable adjustable tappet 23 is interposed between the cam 12 and the plunger 11, but for simplicity it has not been shown in the drawing. 90 The working face 13 of the plunger is arranged so that in its lowest position, as denoted by a, Fig. 2, it coincides with the lower ends of the ports 3 and 4. The plunger has an axial hole 14 extending for a short distance from its working face 13 to a diametral hole 15 drilled through the plunger. In the uppermost position of the plunger, as denoted by the level b, (Fig. 2), attained by the working face 13, the lower edge 100 of the diametral hole 15 is slightly below the 105

upper edge 16 of the port 3 and the corresponding upper edge of the port 4.

- On the lower end of the plunger 11 is centered a collar 17 provided with two diametral projections 18. These projections engage in vertical slots 19 cut in a tubular member 20 which is mounted for a limited rotation in the pump casing. The upper end of the tubular member 20 is formed with teeth 26 which are engaged by teeth in a rack 21 mounted for longitudinal movement within the pump casing. A helical spring 22 is interposed between a shoulder on the sleeve 1 and the collar 17 to bias the plunger 11 against the operating cam 12.
- 15 The operation of the pump may best be understood by referring to the diagram Fig. 3. In this figure the horizontal lines A A' and B B' denote the lower and upper limits of the stroke of the working face 13 of the plunger 11 with respect to the port. It will be understood that the action of the port 4 is exactly the same as that of the port 3, the diametral position of the ports serving to balance the plunger hydraulically and also against side thrust, thereby eliminating uneven wear on the sleeve or plunger to a considerable extent. The horizontal lines C C' and D D' denote the extreme lower and upper positions respectively of the centre of the diametral hole 15 in the plunger. When the plunger is rotated relatively to the sleeve so that the centre of the diametral hole 15 is in alignment with the vertical edge 24 of the port 3, the pump bypasses during the whole portion of its stroke and no fuel delivery occurs. It will be seen that during the movement of the working face 13 of the plunger from the level A A' to the upper edge 16 of the port 3, fuel is by-passed from the chamber 25 through the ports 3 and 4 into the annular chamber 5. Just before the working face 13 reaches the edge 16 of the port, the diametral hole 15 has already passed above the lower corner of the port 3 and by-passing also commences through the axial hole 14 and diametral hole 15 to the annular channel 5 through the ports 3 and 4. After the working face 13 has moved above the edge 16 of the port, by-passing occurs solely through the passageway 14 and 15 until the end of the stroke in which position the hole 15 is still in communication with the annular channel 5 through the ports 3 and 4 as shown at 15d. In this relative position of the plunger and the sleeve, it will be seen that by-passing of the fuel occurs during all of the plunger stroke and therefore no discharge from the pump occurs. In the other extreme relative position of the plunger 11 with respect to the sleeve 1, in which the diametral hole 15 passes beyond the extreme right-hand corner of the port 3, the maximum pumping action takes place since by-passing occurs only during the passage of the working face 13 from its lowermost position A A' to the upper edge 16 of the port. Thereafter during its passage to B B' no by-passing of the fuel takes place as the diametral hole 15 does not pass across the port 3.

It will be evident that between the two extreme relative positions of the plunger and sleeve, any desired quantity of fuel between zero and the maximum value may be pumped by suitable rotation of the plunger 11 with respect

to the sleeve 1. Owing to the inclined edge 27 of the port 3 and the inclined edge 28 of the port 4 the quantity of fuel pumped will be proportional to the angular rotation of the plunger 11.

80 Due to the construction and arrangement of the ports 3 and 4, and the diametral hole in the plunger 11 a symmetrical arrangement is obtained so that the balance of the plunger is not affected by its rotation.

85 It will be evident that the fuel pump hereinbefore described by way of example only may be modified considerably within the scope of the invention.

90 I claim:

A fuel injection pump for internal combustion engines, comprising a cylinder having near its inner end a diametrically opposed pair of substantially triangular ports for connection at their outer ends with a source of fuel under pressure, each of said ports having its inner edge normal to the axis of the cylinder and its outer edge extending obliquely to its first named edge and transversely of the corresponding edge of the other port, a plunger adapted to be reciprocated with a constant stroke in said cylinder to alternately uncover and cover said ports during the outer portions of each of its in and out strokes, said plunger having a diametral passageway and an axial passageway extending from its working face to said diametral passageway, the edge of said diametral passageway nearest the working face of said plunger being spaced from said face a distance less than the greatest distance between the said edges of each of said ports of the cylinder and the edge of said diametral passageway furthest away from the working face of said plunger being spaced at such distance from said face as to be disposed substantially rearwardly of the edges of said ports which are normal to the axis of said cylinder, when the plunger is at its innermost position, whereby communication between the interior of the cylinder and said ports is established through said diametral passageway during the final portion of the instroke of said plunger for by-passing fuel from the cylinder to said ports, the surface of said cylinder inwardly and outwardly beyond said pair of ports and the surface of said plunger inwardly and outwardly beyond said diametral passageway being smooth and imperforate and forming cooperative bearing surfaces between said plunger and cylinder, thus reducing wear on the inner edge of said plunger, equal portions of said ports being disposed on opposite sides of the axis of said plunger to avoid lateral thrust on said plunger, said diametral passageway being located near the upper end of said plunger to provide a short passageway between the working face of said plunger and said ports when said working face passes inwardly beyond said ports, and said ports having sharply defined corners to effect a sudden commencement of the delivery stroke of said plunger, and means for rotating said plunger relatively to the cylinder for varying the duration of communication between the cylinder and said ports through the passageways of the plunger.
